CLAIM

We claim the ornamental design for truck roof fairing, as shown and described.

DESCRIPTION

FIG. 1 is a side elevational view of a first embodiment of the truck roof fairing showing our new design, in a position of use;

FIG. 2 is a side elevational view shown in larger scale, the opposite side elevational view being a mirror image thereof;

FIG. 3 is front view thereof;

FIG. 4 is a top view thereof;

FIG. 5 is a side elevational view of a second embodiment, with the opposite side elevational view being a mirror image thereof;

FIG. 6 is a front view thereof; and,

FIG. 7 is a top view.

The bottom view and rear elevational view, not shown, are plan and unornamented.
